UNITED STATES PATENT OFFICE.

CHARLES H. GILL, OF CHICAGO, ILLINOIS, ASSIGNOR TO UNDERWOOD TYPEWRITER COMPANY, OF NEW YORK, N. Y., A CORPORATION OF DELAWARE.

MARGIN-WARNING MECHANISM FOR TYPEWRITERS.

Application filed February 4, 1924. Serial No. 690,534.

My invention relates to means for automatically and silently warning the operator when a line of typewriting is almost complete and to give such warning at the 5 moment when the operator has just finished the writing of a word upon said line, so that the operator can determine upon the advisability of writing another word upon said line or of carrying said word over to 10 the next following line. In other words, my invention provides means for locking the spacing bar or key of a typewriter against operation at the first attempt when the carriage of the typewriter is in such 15 position relative to the margin stop mechanism that less than a given number of characters may be written upon the same line before the said margin stop mechanism becomes operative to stop the further travel 20 of the carriage. That is, if my mechanism is constructed or adjusted to permit the free operation of the spacing bar or key only when six or more characters may still be printed upon the line, and if a word were 25 completed at a point leaving room for only five more characters, for instance, when the operator attempts to space preparatory to writing a new word, he finds that the spacer key will not operate. Thus, he is apprised 30 of the situation. If the word to be started is one containing in excess of four letters (that being the number of character spaces left on the line after the spacer is operated) he will begin a new line with that word. If 35 the word contains four letters or less, he will again strike the spacer key, which will then operate, and will write the word before beginning a new line.

The advantage of this method of giving 40 warning over the usual employment of a bell that rings at a given number of spaces from the end of a line is that the warning is always given at the end of a word and not, as in the case of the fixed warning, sometimes in the middle of a word or just after starting a long word. It also eliminates the objectionable noise of the bell.

The objects of my invention are, first, to 45 provide means operating in conjunction with existing margin stop mechanism for locking the spacer key or bar against effective movement when an initial attempt is made to operate said key or bar within a given number of spaces of the end of the 55 line as determined by the setting of the

regular margin stop; second, to provide means for unlocking the said spacer key or bar after one attempt to operate the same has been made, so that a second effort to 60 so operate it will be effective; and, third, to provide means for automatically unlocking the said spacer key or bar when a new line is started in the event that no attempt is made to operate the same upon the same line after it becomes locked 65

I attain these objects and others as may hereinafter appear by means of the mechanism illustrated in the accompanying drawings, in which—

Figure 1 is a sectional elevation of a portion of a typewriter embodying my invention; Figure 2 is a fragmentary detail showing the spacer bar in locked position; and Figure 3 is a detail sectional view of the locking rod having the said rod broken 70 away and the rocking arms brought closer together to conserve space in the drawing.

Similar numerals designate similar parts throughout the several views.

11 designates a portion of the movable 80 carriage and 12 a pointer carried by the said carriage 11 and adapted to indicate graduations upon a scale plate 13 secured upon the frame 14 of the machine.

It is thought unnecessary to illustrate or 85 describe in detail the margin stop actuating mechanism, since this forms no part of my invention and is well known to those versed in the art. For the purposes of this disclosure, it is deemed sufficient to indicate the cam actuating member 15 upon the carriage 11 and the cam part 16 pivotally carried upon the rod 17 secured in the frame 14. The cam part 16 is movable longitudinally 90 of and upon the rod 17 and provided with means for securing it to a tilting member 18 which is also pivoted upon the rod 17.

A lever 19 is secured to or made integral with the tilting member 18 in such manner 95 that the lever 19 is moved gradually to the position indicated in broken lines in Figure 1 as the carriage 11 carries the cam actuating member 15 along the cam part 16 and thus tilts the tilting member 18. A key locking means is provided, forming no part 100 of my present invention, and consisting of a rod 20 secured to arms 21 pivoted to the frame 14 at their opposite ends to permit of a rocking motion of the rod 20. When the

lever 19 is swung over to the position indi- 105 110

cated by broken lines in Figure 1, it throws the rod 20, through the rocking motion of the arms 21, into position to engage hook members 22 secured upon or forming parts 5 of key levers 23 which are pivotally mounted in the frame 14. A spiral spring 24 is secured to the frame 14 and to one of the arms 21 in such manner as to so urge the arms 21 and rod 20 as to normally hold the 10 rod 20 out of engagement with the hook members 22.

My present invention consists in providing arms 25 pivoted by means of pins 26 to the frame 14, one at each side of said frame, 15 and connected by a rod 27, the arrangement being for a rocking motion of the arms 25 and rod 27. The lever 19 is provided with a trigger 28 pivoted upon the lever 19 by a pin 29 so that the lower portion of the trigger 28 (which is wider and heavier than the upper portion of trigger 28) extends below the lower end of the lever 19. A pin 30 in the lever 19 prevents the trigger 28 from swinging in one direction and gravity normally retains the trigger 28 in the position shown in Figure 2. In normal position the rod 27 lies in the pathway of the trigger 28 and is adapted to be urged over to the position indicated by the broken lines in Figure 30 1 by the lever 19 somewhat before that lever 19 has moved sufficiently to engage the rod 20 with the hook members 22. In the position shown in Figure 3, the arms 25 have been urged forwardly to vertical position 35 against the resistance of the spiral springs 31. In this position, the rod 27 is in the pathway of a projecting part 32 of the spacer lever 33 of the typewriter and will be engaged by the projecting part 32 before 40 the spacer bar 33 can be moved downwardly enough to operate the spacing mechanism with which it is adapted to be operatively connected. Neither the spacing mechanism nor the connection between same and the 45 spacer bar are illustrated as these are well known constructions and form no part of my present invention. It is thought to be sufficient to illustrate a spacing key 34 upon a spacing lever 33 pivoted upon the frame 50 14 by means of pins 35 and held in normal position by springs 36, and to state that downward movement of the spacing lever 33 may be utilized to actuate a spacing mechanism or escapement.

55 When the projecting part 32 of the spacing lever 33 bears against the rod 27 in the downward movement of the spacing lever 33 the rod 27 and arms 25 are forced downwardly against the resistance of the springs 60 31, this downward movement being permitted by slots 37 in the arms 25, through which slots 37 the arms 25 are pivoted by the pins 26 upon the frame 14, thus stopping the downward movement of the spacing lever 33 when the pins 26 contact with the upper

ends of the slots 37 and before such movement has become sufficient to actuate the escapement mechanism. When pressure is removed from the spacer key 34 and the spacing lever 33 is allowed to be returned toward its normal position by the urge of the springs 36, the springs 31 will throw the arms 25 and rod 27 back to their normal position as shown in full lines in Figure 1 and in broken lines in Figure 2. Should the 75 spacer key 34 be pressed again thereafter, the spacing lever 33 will be free to move downwardly sufficiently to actuate the escapement mechanism. In order that the lever 19 may pass the rod 27 upon the return of the lever 19 to its normal position, the trigger 28 is adapted to trip and permit such return.

Pins 38 in the frame 14 act as stops to limit the swing of the arms 25 in one direction and pins 39 in the frame 14 acts as stops to limit the swing of the arms 25 in the opposite direction.

In operation, the lever 19 is thrown forward gradually as the carriage of the typewriter approaches the position that is to bring an end to the writing line, the lever 19 being moved by the well understood camming action between the parts 15 and 16 and the consequent rocking of the rocker or tilting member 18. When the lever 19 has moved forward a short distance the trigger 28 contacts with the rod 27 and further forward movement of the lever 19 thus rocks the arms 25 on their pivoting pins 26 carrying with them the rod 27. When the carriage 11 has moved to within a predetermined number of spaces of the termination of the writing line, or of the point where the ordinary line locking mechanism becomes effective, the lever 19 will have swung forwardly to a degree sufficient to have carried the rod 27 to a position in the path of the projecting portion 32 of the spacing lever 33 so that any attempt to operate the spacing lever 33, through the spacing key 34, will cause the projecting portion 32 to contact with the rod 27. The spacing lever 33 will then be free to swing downwardly by pressing the rod 27 and arms 25 downwardly against the resistance of the springs 31. The slots 37 in the arms 25 permit this downward sliding movement of the arms 25 on the pivoting pins 26. When the upper ends of the slots 37 contact with the pivoting pins 26 no further downward movement of the arms 25 and rod 27 are permitted and the spacing lever 33 is thus locked against swinging downwardly further. Since the slight movement permitted to the spacing lever 33 before becoming locked is insufficient to actuate the escapement mechanism, it will be evident that this movement of the spacing lever 33 is inoperative. It will also be evident that the failure of the spacing key 34 to move downwardly under pressure by the 130

operator more than a small part of its ordinary movement will apprise the operator that it is locked against effective operation.

When the pressure of the operator on the spacing key 34 is discontinued the spacing lever 33 will be returned to its normal position by the spring 36 and, as the rod 27 is then below the reach of the trigger 28, the arms 25 will be swung backwardly and drawn upwardly by the spring 31 to abut against the stop pins 38. A second pressure on the spacing key 34 will now freely operate the spacing lever 33 and the escapement mechanism until the regular line locking mechanism is brought into action by the further forward swing of the lever 19 carrying the rod 20 to such position as to engage the rod 20 with the hooks 22 for locking the printing keys.

When the carriage is returned to begin a new line of writing, the camming action of the parts 15 and 16 ceases and the lever 19 is drawn back to its normal position, as shown in full line in Figure 1, by the action of the spiral spring 40 secured to the lever 19 and to the frame 14. The trigger 28 is adapted to pass the rod 27 as the lever 19 moves to its normal position because of the trigger 28 being hingedly mounted on the lever 19.

Because of the length of the projecting portion 32 of the spacing lever 33, any first attempt to effectively operate the spacing lever 33 from the time the rod 27 first comes within the path of the portion 32 to the time that the regular line stop mechanism becomes effective will be prevented by the rod 27 and any second attempt to effectively operate the spacing lever 33 will be successful.

It will be evident that numerous departures from the precise construction illustrate and described herein are possible without departing from the spirit of my invention and I, therefore, do not limit the scope of my invention to the particular construction described, the only limits placed upon its scope being those imposed by the following claims and by the prior state of the art.

I claim:

1. In margin warning mechanism for typewriters, the combination of a spacing lever, a carriage, a multiplicity of type levers, and locking mechanisms operative successively for first rendering said spacing lever ineffective to feed the carriage, then effective to feed the carriage and prevent the operation of said type levers.

2. In a margin warning mechanism for typewriters, the combination of a spacing lever, a multiplicity of type levers, a letter feeding carriage, and locking mechanisms operative successively for first rendering said spacing lever ineffective to feed the carriage without affecting the operation of said type

levers, then effective to feed the carriage and to prevent the operation of said type levers.

3. In margin warning mechanism for typewriters the combination of a spacing lever, a multiplicity of type levers, locking mechanism adapted to render said spacing lever inoperative without affecting the operation of said type levers, and means actuated by one operative action of said locking mechanism for rendering said locking mechanism inoperative.

4. In margin warning mechanism for typewriters the combination of a spacing lever, a multiplicity of type levers, a movable carriage, locking mechanism adapted to render said spacing lever inoperative without affecting the operation of said type levers, means adapting a portion of the movement of said carriage in one direction to render operative the said locking mechanism, and means actuated by one operative action of said locking mechanism for rendering said locking mechanism inoperative.

5. In margin warning mechanism for typewriters the combination of a spacing lever, a multiplicity of type levers, a movable carriage, locking mechanism adapted to render said spacing lever inoperative without affecting the operation of said type levers, means adapting a portion of the movement of said carriage in one direction to render operative the said locking mechanism, and means actuated by one operative action of said locking mechanism for rendering said locking mechanism inoperative during the continued movement of the said carriage in the said one direction.

6. In margin warning mechanism for typewriters the combination of a detent adapted to be moved into operative position by a portion of the movement in one direction of a typewriter carriage while the said carriage is yet some distance from the limit of movement of said carriage in said direction, a spacing lever adapted to contact with said detent whenever said spacing lever is operated while said detent is in operative position so that said spacing lever shall then be inoperative for spacing, and means for rendering said detent inoperative and said spacing lever operative after one operation of said detent during any one travel of said carriage in said one direction.

7. In margin warning mechanism for typewriters the combination of a spacing lever, a movable carriage, line stop mechanism adapted to lock the said carriage against movement beyond an adjustable limit in one direction, locking means actuated by movement of said carriage and adapted to lock the said spacing lever against operative movement whenever the said carriage travels to within a predetermined distance of the limit of movement of said carriage in one direction, and

automatic means actuated by the inoperative movement of said spacing lever for rendering the said locking means inoperative to lock the said spacing lever against a following effort to operate said spacing lever.

8. The combination with a typewriting machine having a letter-feeding carriage, a spacing key therefore, and type-operating keys, of means for limiting an initial depression of said spacing key sufficiently to prevent actuation of the letter-feeding mechanism of the carriage after completion of a word within a predetermined typing zone near the end of the carriage-travel, said limiting means becoming ineffective upon release of the spacing key, so that upon subsequent depression of said spacing key, the carriage may be further letter-spaced and additional typing added to the line.

9. The combination with a typewriting machine having a letter-feeding carriage, a spacing key therefor, type-operating keys, and locking means therefor, of means for limiting an initial depression of said spacing key sufficiently to prevent actuation of the letter-feeding mechanism of the carriage

after completion of a word within a predetermined typing zone near the end of the carriage-travel, said limiting means becoming ineffective upon release of the spacing key, so that upon a subsequent depression of said spacing key, the carriage may be further letter-spaced and additional typing added to the line, means for operating said limiting means, said operating means being also effective to cause said locking means to lock the type-operating keys as the carriage reaches the end of its travel.

10. In margin warning mechanism for typewriters, the combination of a spacing lever, a multiplicity of type levers, a letter feeding carriage, and locking mechanisms operative successively for first rendering said spacing lever ineffective to feed the carriage without affecting the operation of said type levers, then effective to feed the carriage and to prevent the operation of said type levers, the letter feeding movement of the carriage causing said locking mechanisms to lock the spacing lever when said carriage reaches a predetermined point adjacent the end of its travel.

CHARLES H. GILL.
